Primary Examiner — David G Muller*Assistant Examiner* — Christina Gabrielle Cosden(74) *Attorney, Agent, or Firm* — KDW Firm PLLC(57) **CLAIM**

The ornamental design for anchor release device, as shown and described.

DESCRIPTION

FIG. 1 is a front perspective view of the anchor release device showing my new design;

FIG. 2 is a front elevation view;

FIG. 3 is a rear elevation view;

FIG. 4 is a left side elevation view;

FIG. 5 is a right side elevation view;

FIG. 6 is a top plan view;

FIG. 7 is a bottom plan view; and,

FIG. 8 is a perspective view of the anchor release device in an installed condition on an anchor with the anchor shown in broken lines.

The broken/dotted lines are for illustrative purposes only with respect to the environment and form no part of the claimed design.
